UNITED STATES PATENT OFFICE

JOSEPH GIOIOSA, MILTON, MASSACHUSETTS

MACHINE FOR FORMING WATERPROOF TUBING AROUND FIREWORK FUSE MATERIAL

Application filed August 19, 1931. Serial No. 557,974.

This invention relates to a machine for forming tubing around firework fuse material, particularly a tubing which will be impervious to moisture.

5 The object of the invention is to provide a machine of simple construction which will quickly and effectively form a continuous length of paper tubing around a continuous length of firework fuse material, said tubing being constructed of a plurality of continuous strips of sheet material, one of which is impervious to moisture.

10 Another object of the invention is to provide a means for applying an adhesive material to the tubing in such a manner that the loose edge of the outer strip of sheet material will be securely fastened and the completed tubing perceptively stiffened.

15 Still another object of the invention is to provide a means for quickly and effectively drying the adhesive material.

20 The invention consists in a machine for forming a moisture-resisting tubing of sheet material around firework fuse material as set forth in the following specification and particularly as pointed out in the claims thereof.

25 The machine is an improvement over a machine for which I have applied for Letters Patent of the United States Serial No. 526,108, filed March 28, 1931.

Referring to the drawings:

30 Fig. 1 represents a plan view of a machine for forming tubing embodying my invention.

35 Fig. 2 is an enlarged transverse section taken on the line 2—2, Fig. 1.

Fig. 3 is an enlarged vertical longitudinal section taken on the line 3—3 of Fig. 1.

40 Fig. 4 is an enlarged front elevation of a portion of the parts illustrated in Fig. 1.

Fig. 5 is an enlarged transverse section partly in elevation taken on the line 5—5 of Fig. 4.

45 Fig. 6 is an enlarged transverse section taken on the line 6—6 of Fig. 4.

Fig. 7 is an enlarged transverse section partly in elevation taken on the line 7—7 of Fig. 4.

50 Fig. 8 is an enlarged transverse section taken on the line 8—8 of Fig. 4.

Fig. 9 is an enlarged transverse section taken on the line 9—9 of Fig. 1.

Fig. 10 is a side elevation of the tubular member which prevents the paper tubing from collapsing during the feeding operation.

Like numerals refer to like parts throughout the several views of the drawings.

In the drawings, 12 is a frame constructed in the form of a rectangular plate, and 13 and 14 are strips of sheet material, preferably paper, which are led from rolls of said material to a point above one end of said frame. The strip of paper 13 is preferably wider than the strip 14, and the latter strip is treated with or constructed of a material which will render it moisture proof. The strips of paper 13 and 14 are fed between a pair of vertical guide members 15, preferably formed of rubber and mounted upon vertical studs 16.

From the guide members 15, the strips of material 13 and 14 pass to and through a frusto-conical forming member 17 which is mounted upon a bracket 18 in turn supported upon the frame 12. The frusto-conical forming member 17 tapers in the direction toward which the sheets of material are fed. Mounted in the frusto-conical member 17 and positioned eccentrically with relation thereto is a frusto-conical guide member 19, the outer periphery of which is secured to the inner surface of the frusto-conical member 17. By mounting the member 19 within the member 17 a crescent-shaped space 20 is formed within the guide member 17 and it is through this space that the strips of sheet material 13 and 14 pass; and when said strips emerge from the forming member 17 their adjacent faces contact with each other and they are bent in semi-tubular form, see Figs. 5 and 6.

From the forming member 17 the strips of sheet material 13 and 14 pass to a spiral forming member 21 mounted upon a bracket 22 in turn supported upon the frame 12. The forming member 21 tapers longitudinally thereof in the direction toward which the strips of sheet material are fed and is spiral in cross-sectional contour, see Fig. 7. As the strips of sheet material are fed into the form-

ing member 21 they are progressively bent into spiral form and reduced in diameter, and when said strips emerge from said member, the narrow strip 14 has assumed a tubular 5 formation and one edge portion of the wide strip 13 has assumed a tubular formation around the strip 14, while the remainder of the strip 13 extends laterally therefrom at 23, see Fig. 8.

- 10 From the forming member 21 the partially formed tubing extends into and through a reservoir 24 for a suitable adhesive material which contacts directly with all of the exposed portion of the strip 13, which includes 15 both faces of the laterally projecting portion 23 of said strip. In passing outwardly from the reservoir 24 the sheet material passes through a rubber tube 25 which acts to fold the portion 23 of the strip 13 against the 20 tubular portion of said strip and at the same time wipe the tubing and limit the amount of adhesive material which is allowed to adhere to the outer periphery of said tubing.

From the reservoir 24 the completely 25 formed tubing 26 passes into and through a drying device 27 embodying therein a container 28 in which a quantity of water is located. In passing through the drying device 27, the tubing 26 passes through a rigid 30 tubular member 29 which prevents the water from contacting with said tubing. The container 28 rests upon an electrical heating apparatus 30 of any suitable construction and the water within the container 28 is heated 35 thereby. As the tubing 26 emerges from the tubular member 29 it passes into and through another tubular member 31 constructed of rubber, which exerts a yielding pressure against the periphery of said tubing.

40 The strips of sheet material 13 and 14 are fed through the forming members 17 and 21, reservoir 24 and drying device 27 by means of feed rolls 32 and 33 which are located upon 45 opposite sides of the completed tubing 26 adjacent to the point where said tubing emerges from the tubular member 31. The feed rolls 32 and 33 are formed of rubber or other suitable material which will frictionally engage the tubing and exert a strong 50 pulling action thereon. The rolls 32 and 33 are rigidly fastened to a driving shaft 34 and countershaft 35 respectively, and said shafts are connected together and rotate in unison by gears 36 and 37. The driving shaft 34 may be driven in any suitable manner.

To prevent the completed tubing 26 from collapsing between the feed rolls 32 and 33 a tubular member 38 is positioned within the 60 completed tubing at the point where said rolls press thereagainst. The tubular member 38 is prevented from being drawn forwardly with the tubing 26 by being connected by means of a wire 39 with the forming member 65 17, where a hook portion 40 formed upon the

wire is attached to the rear end of the forming member 17, see left hand end of Fig. 4.

An endless piece of fuse material A, well known in the art, is fed by means of the completed tubing 26 through the various tube-forming members, and the strips of sheet material 13 and 14 are bent around said fuse as the latter passes through the forming members. The strip of fuse material A is guided into the forming member 17 by means of a guide roll 41 mounted upon a bearing 42, being guided to said guide roll through a tubular guide member 43 mounted in a bracket 44 supported upon the frame 12.

70 The general operation of the mechanism hereinbefore specifically described is as follows:—Assuming that the strips of sheet material 13 and 14, positioned as illustrated in Fig. 2, have been threaded successively through the forming members 17 and 21, reservoir 24, rubber tube 25, rigid tubular member 29 and rubber tube 31, and at the same time formed into a tube around the continuous piece of fuse material A, the feed rolls 32 and 33 are started in operation to 75 pull the strips of sheet material through the members mentioned. As the strips of sheet material pass through the frusto-conical forming member 17, the flat strips of material are bent into semi-tubular form, with the side strip 13 partly enclosing the narrow strip 14, and at the same time both of the strips of material are caused to taper slightly in the direction toward which they are fed.

80 From the forming member 17 the partially formed tubing is fed to the spiral forming member 21, where it is still further bent to entirely enclose the fuse material A and to 85 assume a spiral cross-sectional form which, furthermore, also tapers in the direction to 90 the side strip 13 partly enclosing the narrow strip 14, and at the same time both of the strips of material are caused to taper slightly in the direction toward which they are fed.

95 From the forming member 21 the partially formed tubing passes into the reservoir 24 and through the adhesive material which is contained therein, emerging from said reservoir 100 through the rubber tube 25, which acts to force the portion 23 of the strip of sheet material 13 against the tubular portion of said strip and also to wipe the excess of adhesive 105 from the periphery of the tubing. The tubing then passes to the drying device 27 where upon passing through the rigid tubular member 29 it is subjected to a sufficient amount 110 of heat to cause the adhesive material to dry quickly, and finally, the tubing passes through another rubber tube 31 where it receives a final wiping operation. As the tubing 26 is fed through the various forming members the endless piece of fuse material A will be pulled along in unison with the 115 tubing and the strips of sheet material 13 and 14 will be progressively formed around the fuse material.

120 It is evident that if it is so desired, the feeding mechanism for the tubing may be 125

omitted and the tubing fed through the apparatus by hand.

I claim:

1. A machine of the character described
5 having, in combination, means to position a plurality of strips of sheet material face to face, and means to bend said strips longitudinally thereof into tubular form, one within another.

10 2. A machine of the character described having, in combination, means to position a plurality of strips of sheet material face to face, means to bend said strips longitudinally thereof into tubular form, one within another, and means to apply an adhesive material to the outer of said tubular strips.

15

3. A machine of the character described having, in combination, means to position a plurality of strips of sheet material face to face, means to bend said strips longitudinally thereof into tubular form, one within another, means to apply an adhesive material to the outer of said tubular strips, and means to dry said adhesive material.

25 4. A machine of the character described having, in combination, means to position a plurality of strips of sheet material face to face, means to bend said strips longitudinally thereof simultaneously one around another into semi-tubular form, means to bend said semi-tubular portions into spiral form, and means to finally bend said spiral portions into tubular form.

5. A machine of the character described
35 having, in combination, means to position a plurality of strips of sheet material face to face, means to bend said strips longitudinally thereof simultaneously one around another into semi-tubular form, means to bend
40 said semi-tubular portions into spiral form, means to apply an adhesive material to the outer of said partly bent strips, and means to finally bend the spiral portion into tubular form.

45 6. A machine of the character described having, in combination, means to position a plurality of strips of sheet material face to face, means to bend said strips longitudinally thereof simultaneously one around another 50 into semi-tubular form, means to bend said semi-tubular portions into spiral form, means to apply an adhesive material to the outer of said partly bent strips, and means to finally bend the spiral portions into tubular form 55 and wipe the excess of adhesive material from the periphery of the tubing.

7. A machine of the character described having, in combination, means to position a plurality of strips of sheet material face to face, means to bend said strips longitudinally thereof simultaneously one around another into semi-tubular form, means to bend said semi-tubular portions into spiral form, means to apply an adhesive material to the outer of said partly bent strips, means to finally bend

65 said partly bent strips, means to finally bend

the spiral portions into tubular form and wipe the excess of adhesive material from the periphery of the tubing, and means to heat the tubing.

8. A machine of the character described having, in combination, means to position a plurality of strips of sheet material face to face, a frusto-conical forming member, a spiral forming member, means to feed the strips of sheet material in unison through the forming members, means to apply an adhesive material to a strip of sheet material during the feeding movement, and means to wipe the strip having the adhesive material thereon. 70
75

9. In combination, means for feeding a continuous piece of fuse material and a plurality of strips of sheet material of different widths positioned face to face, means to bend the wider of said strips around the narrower of said strips and both of the strips to form a tubing around said fuse, means to apply an adhesive material to the outer of said bent strips, and means to wipe the periphery of said tubing.

10. In combination, means for feeding a continuous piece of fuse material and a plurality of strips of sheet material of different widths positioned face to face, means to bend the wider of said strips longitudinally thereof to partially enclose the fuse, means to engage the partially bent wide strip and progressively force both of the strips into spiral form around the fuse, means to apply an adhesive material to the outer bent strip, and means to finally bend the spiral portions of both strips into tubular form around the fuse. 90
95
100

12. In combination, means for feeding a continuous piece of fuse material and a plurality of strips of sheet material of different widths positioned face to face, means to bend the wider of said strips longitudinally thereof to partially enclose the fuse, means to engage the partially bent wide strip and progressively force both of the strips into spiral form around the fuse, means to apply an adhesive material to the outer bent strip, means to finally bend the spiral portions of both strips into tubular form around the fuse, and means to heat the formed tubing to dry the adhesive material thereon.

13. In combination, means for feeding a 130

- continuous piece of fuse material and a plurality of strips of sheet material of different widths positioned face to face, means to bend the wider of said strips longitudinally thereof
5 to partially enclose the fuse, means to engage the partially bent wide strip and progressively force both of the strips into spiral form around the fuse, means to apply an adhesive material to the outer bent strip, means to finally bend the spiral portions of both strips into tubular form around the fuse and wipe the excess of adhesive material from the periphery of the formed tubing, a tubular member through which the formed tubing is fed,
10
15 and means to heat said tubular member.

In testimony whereof I have hereunto set my hand.

JOSEPH GIOIOSA.
